Application November 15, 1951, Serial No. 256,553

10 Claims. (Cl. 292—280)

1

This invention relates to a latch control mechanism for swinging doors, particularly the doors of automobile or other vehicle bodies, an object of the invention being to provide an improved door latch mechanism which is characterized by its simplicity and compactness in construction and which is economical to manufacture, comparatively quiet in operation and efficient in use.

The improved door latch mechanism of the present invention comprises a rotary latch device, detent means for holding the latch device in latching position, detent release lever means for disengaging the detent means from the latch device, and a pivoted member or lever having a blocking means which may be positioned in blocking relation to a blocking portion on the detent release lever to render the latter inoperative to effect disengagement of the detent means from the latch device.

It is an object of the present invention to provide improved means actuatable by the inside door handle remote control mechanism for shifting the blocking lever into blocking position with respect to the detent release lever means upon manipulation of the inside door handle in one direction, said improved means also being actuatable to effect restoration of the blocking lever to non-blocking position and to simultaneously disengage the detent means from the latch device upon manipulation of the inside door handle in the opposite direction.

Other objects and features of this invention will appear in the following description and appended claims, reference being had to the accompanying drawings forming a part of this specification wherein like reference characters designate corresponding parts in the several views.

Fig. 1 is a sectional elevation illustrating the mechanism mounted on the case plate of a door latch mechanism constructed in accordance with the present invention.

Fig. 2 is a sectional elevation taken substantially through lines 2—2 of Fig. 1 and also illustrating a remote control handle mechanism for operating the latch mechanism from the inside of the vehicle door.

Fig. 3 is a fragmentary sectional elevation illustrating the relationship in latched position of the rotary bolt of the latch mechanism to a 50 striker or keeper device mounted on a body pillar.

Before explaining in detail the present invention it is to be understood that the invention is not limited in its application to the details of 55

2

construction and arrangements of parts illustrated in the accompanying drawings, since the invention is capable of other embodiments and of being practiced or carried out in various ways. 5 Also it is to be understood that the phraseology or terminology employed herein is for the purpose of description and not of limitation.

In the drawings there is illustrated, by way of example, a certain embodiment of the present invention as applied to the door and door frame structures of an automobile body. The latch device constructed in accordance with the illustrated embodiment of the invention comprises a case plate 10 which is provided with screw bosses 10a which are adapted to receive screws for fastening the case plate to the inner side of the jam portion or free edge wall of the vehicle door, the case plate 10 having a flange 11 which is adapted to be positioned along the inner panel 16 of the door. The present latch device is provided with a rotatable toothed latch or bolt 12 positioned at the outer face of the case plate 10, this latch or bolt having an integral projecting stud shaft or pivot 13 extending through an aperture 15 in the case plate which is formed as a bearing for the stud shaft. The inner end of the stud shaft 13 is flattened and extended through a correspondingly shaped aperture in a rotatable toothed detent engaging member or ratchet member 14 and is riveted thereto. From the foregoing construction it will be seen that the toothed latch or bolt 12 is rigidly secured to the detent engaging member or ratchet member 14, being concentric therewith on the stud 13.

The rotatable latch or bolt 12 is formed with a number of radially projecting toothlike projections 12a, such as five, which are spaced equally entirely around the periphery of the latch so as to provide in effect a gear type latch. The detent engaging member or ratchet 14 is formed around its periphery with a number of abutments or shoulders 14a which correspond in number to the number of toothlike projections 12a. Thus, in the illustrated embodiment the latch 12 has, for example, five toothlike projections 12a and the detent engaging member 14 has five equally spaced detent engaging abutments or shoulders 14a.

Cooperable with the peripheral notched edge of the ratchet 14 is a swinging detent, pawl or dog 15 pivotally mounted on a shoulder rivet 16 secured to the case plate 10. The detent 15 is a two arm member having one arm 17 extending in a substantially downwardly direction and cooperable with the teeth or projections 12a of the ratchet member 14. The detent arm 17 is en-

gageable with any one of the teeth 14a in the manner shown in Fig. 1 to hold the ratchet member and hence the bolt 12 in locking position against rotation in a counterclockwise direction. The second arm 18 of the detent member 15 extends in a substantially horizontal direction toward the flange 11. The detent arm 17 has a further downwardly extending extension 19 for a purpose to be hereinafter explained.

Associated with the detent is a vertically extending detent actuating or release lever 20 which is pivoted intermediate its ends upon the shoulder rivet or stud 16, the same stud on which the detent 15 is pivotally mounted on the case plate. The release lever 20 has a lever arm 21 extending downwardly below the pivot 16 and overlying a substantial portion of the detent arm 17 and its extension 19. The lever arm 21 is provided with an aperture 22 through which projects a pin 23 extending upwardly from the detent arm 17. By virtue of this construction the lever arm 21 and the detent arm 17 are so interconnected that if the detent release lever 20 is swung about its pivotal axis in a counterclockwise direction as viewed in Fig. 1, the edge wall 22a of the aperture 22 will engage the lug 23 and thereby swing the detent member 15 about its pivotal axis in a counterclockwise direction as viewed in Fig. 1, and the detent arm 17 will be disengaged from the ratchet member 14.

The detent release lever 20 has an upwardly extending lever arm 24 formed with a flange 24a thereon. This lever arm 24 is adapted to be engaged on the outer side of the flange 24a by an outside manually operable means, such as a push button 25, for imparting the pivotal or swinging movement to the detent release lever 20 about its pivot 16 necessary to cause disengagement of the detent 15 from the ratchet 14.

The detent arm 17 is yieldingly urged toward the ratchet 14 and the release lever 20 is similarly urged toward its normal position seen in Fig. 1 by means of a single coiled spring 26 anchored at its inner end to a kerf 27 in the stud 16. This spring has a downwardly extending arm 26a engageable with a portion of the pin 23 projecting through the aperture 22 in the release lever 20 and urges the arm 17 and therefore the whole detent member 15 in a clockwise direction, as seen in Fig. 1, about the pivotal axis 16 so as to yieldingly hold the detent arm 17 in latching engagement with a tooth 14a of the ratchet 14. Due to the interlocking connection between the lever arm 17 and the release lever arm 21, the spring 26 will also function to urge the lever arm 21 in a clockwise direction about the pivotal axis 16. The lever arm 24 will thus be urged outwardly so as to be maintained in the normal non-operating position shown in Fig. 1. Thus, a single spring 26 is utilized to maintain the detent and release lever in their normal positions.

In accordance with the embodiment of the invention herein illustrated means is provided for restraining or blocking the detent release lever 20 against operation from the outside of the door. The blocking means comprises a lever 28 pivoted intermediate its ends on a stud 29 secured to the case plate 10. As illustrated, the pivot axis of the blocking lever 28 is located below the pivot axis of the ratchet 14 and the lever 28 extends in a substantially horizontal direction. At its outer end 28a, the right end as viewed in Fig. 1, the blocking lever is provided with a flange 30, which flange, when the blocking lever 28 is in the position shown in Fig. 1, lies in the path of swinging movement of the lower end or blocking por-

tion 21a of the arm 21 of the detent release lever 20 and thereby blocks swinging movement of the lever 20 in a counterclockwise direction. Since it is necessary for the detent release lever 20 to swing in a counterclockwise direction in order that the interconnection between the release lever 20 and the detent 15 result in movement of the detent arm 17 out of engagement with the ratchet 14, the relationship of the flange 30 to the end 21a of the release lever arm 21 renders the outer manually operable means, such as the push button 25, inoperative to release the latch mechanism from the outside of the door and the door cannot be opened.

The present latch device incorporates a remote control mechanism so constructed as to permit release or disengagement of the detent means 15 by operation of the inside door handle independently of the release lever 20 and regardless of whether the latter is blocked against swinging movement through the medium of the blocking lever 28. This remote control mechanism is preferably manually actuated from the inside of the door remote from the case plate 10 by means of a door handle 31 which may be turned or swung in two directions. Referring particularly to Fig. 2, the remote control mechanism comprises a bell crank or two arm lever 32 pivoted at 33 through the medium of a shoulder rivet to the case plate flange 11. The bell crank 32 has a longitudinally extending arm 32a overlying at its outer end the detent means arm 18. The bell crank 32 also has a depending lever arm 32b pivotally connected by a pivot or shoulder stud 34 to the forward end of a remote control link 35 which at its opposite end is pivoted at 36 to the upper end of a swinging lever 37. This lever is attached to the shank or shaft 38 of the inner door handle, this shaft being journaled in a mounting plate 39 and bracket 40 attached thereto. A substantially U-shaped spring 41 is mounted on the bracket 40 so that the two upstanding legs 41a are in engagement with opposite sides of the lever 37. The legs 41a function to return the lever 37 and therefore the handle 31 to its normal position after the door handle has been released. The base of the spring 41 is provided with an indentation 41b adapted to be seated in a notch 37a in the lower end of the lever 37 when the latter is in its normal position. This construction provides an anti-rattle means to hold the remote control mechanism against vibration induced movements.

Regardless of whether the release lever 20 is blocked or unblocked, the foregoing remote control mechanism construction permits the door to be unlatched from the inside. Turning movement of the inside door handle 31 in a counterclockwise direction as viewed in Fig. 2 will cause the bell crank lever 32 to be swung so as to depress the arm 32a which will result in the detent arm 18 being depressed. Depression of the detent arm 18 results in pivotal movement of the detent means 15 in a counterclockwise direction as viewed in Fig. 1 thereby causing the detent arm 17 to become disengaged from the ratchet 14 thus permitting free rotation of the bolt 12.

As previously mentioned, the detent arm 17 has an extension 19 which extension is utilized to swing the blocking lever 28 from release lever blocking position to non-blocking position in the event that the latch mechanism is released by actuation of the inside handle operated remote

control mechanism while the blocking lever is in blocking position. As shown in Fig. 1, the end 28a of the blocking lever 28 extends between the surface of the case plate 10 and the under surface of the lower end of the lever arm 21 when the flange 30 of the blocking lever 28 is in blocking position relative to the blocking portion 21a of the lever arm 21. The upper edge of the blocking lever end 28a is formed as a cam surface 42 which lies in close proximity to the end of the detent arm extension 19 when the blocking lever is in blocking position. Upon pivotal actuation of the detent 15, as occurs upon swinging of the inside door handle in a counterclockwise direction as viewed in Fig. 2, the end of the extension 19 will strike the cam edge 42 of the blocking lever 28 and swing the latter downwardly to a position in which a toggle spring 43 will cross its dead center position and urge the blocking lever to its full unblocked position as governed by a stop 44 located in the case plate 10 in position to engage the inner end 28b of the lever 28.

The toggle spring 43 has one end seated in an aperture in the end 28b of the blocking lever 28 and its other end in an aperture in the case plate 10 and is provided to yieldingly urge and hold the blocking lever 28 toward its upper and lower limits of movement.

In the present invention means is provided under the control of the inside door handle and remote control mechanism for swinging the blocking lever 28 into blocking position. This may be accomplished by turning the inside door handle in a direction opposite to that which it is turned to cause disengagement of the detent means from the ratchet 14. A bell crank or two arm lever 45 is pivoted at 46 through the medium of a shoulder rivet to the case plate flange 11. As shown in Fig. 2, the pivot axis of the bell crank 45 is vertically spaced below the pivot axis of the bell crank 32. The bell crank 45 has a longitudinally extending arm 45a which overlies at its outer end the end 28b of the blocking lever 28, the arm 45a being in immediate abutting or opposing relation to the upper edge of the end 28b when the blocking lever is in non-blocking position, that is, with the end 28b in abutting relation to the stop 44 and the blocking flange 30 out of blocking position relative to the blocking portion 21a on the release lever arm 21. The bell crank 45 also has an upwardly extending arm 45b having a lost motion slot 47 adapted to receive the shoulder stud 34 which pivotally connects the bell crank 32 to the draft link 35. The lost motion slot 47 permits the stud 34 to move upwardly relatively to the pivot axis of the bell crank 45 as the stud 34 is swung about the pivot axis of the bell crank 32 since it is fixed to the arm 32b of the latter. It will be readily understood that the shoulder stud could be fastened to the arm 45b of the bell crank 45 in which case the slot 47 would be placed in the arm 32b of the bell crank 32.

Thus, to move the blocking lever 28 from non-blocking to blocking position it is only necessary to swing the inside door handle in a clockwise direction as viewed in Fig. 2 whereupon the bell crank 45 will be swung so as to depress the arm 45a thereon. The arm 45a upon being depressed will abut the upper edge of the arm 28b of the blocking lever 28 causing the same to be swung so as to position the blocking flange 30 thereon into locking position relative to the blocking portion 21a of the release lever 20.

As has been described, swinging of the inner door handle in the opposite or counterclockwise direction as viewed in Fig. 2 results in the bell crank 32 pivotally actuating the detent means 15 so that the extension 19 thereof will abut the cam edge 42 of the blocking lever 28 and swing the same back to non-blocking position. Accordingly, if the vehicle door is locked from the inside by swinging the inner door handle into locking direction the blocking lever 28 is automatically restored to non-blocking position as soon as the inner door handle is swung in the opposite direction to permit egress through that door of the vehicle.

In the event that the inner door handle is swung to place the blocking lever 28 in blocking position while the door is in an open position, the extension 19 acts as an automatic kickout or restoration means. Rotation of the ratchet 14 in a clockwise direction as viewed in Fig. 1, which rotation occurs upon engagement of the rotary bolt 12 with the striker or keeper device, causes the abutments 14a to engage the detent arm 17 and pivot the detent means 15 in a counterclockwise direction as viewed in Fig. 1. The extension 19 thus will engage the cam edge 42 causing the blocking lever 28 to be swung to non-blocking position. The foregoing construction and arrangement ensures against the parts of the latch mechanism remaining in the locked position if inadvertently placed therein and the door then being closed.

An illustrative means for swinging the blocking lever 28 through a key controlled device operable from the outside of the door comprises a pin or shaft 48 of a conventional key operated cylinder 49. The pin 48 is mounted for movement eccentrically of the axis of the key cylinder mechanism 49 and extends through an aperture 50 in the flange 30 of the blocking lever 28. Thus, when the shaft 48 is turned as the result of turning movement exerted on a key inserted in the key operated device, the blocking lever may be swung either into or out of blocking position as desired.

Fig. 3 of the drawings illustrates the cooperative relationship between the rotary toothed latch or bolt 12 and the keeper or striker device, generally designated 51, to hold the door in latched position. In general the keeper or striker 51 comprises a C-shaped structure having upper and lower body portions 52 and 53, respectively. The lower body portion 53 is formed at its lower edge with two integral depending tooth-like projections 54 and 55 with which the teeth 12a of the latch bolt 12 mesh to hold the door in either final or safety locking position. When an adjacent pair of teeth 12a embrace and engage the tooth 55 the door is in safety locking position, and when an adjacent pair of teeth 12a embrace the tooth 54 of the striker, the bolt is in final locking position.

The upper surface 53a of the lower body portion 53 forms an inclined ramp engageable by a suitably contoured dovetail or abutment 56 fastened to the outer face of the case plate 10. A yieldable wedging means is carried on the underside of the upper body portion 52 of the striker device and engages the upper surface of the dovetail or abutment 56 to firmly hold the door against vibratory movement in a vertical plane. The wedging means in the present instance comprises a wedge block 57 controlled by a compression spring 58, the wedge block and spring being slidably retained within a recess 60 in the lower surface of the upper body portion 52 by means of a guide rod 59 fastened to the end walls of the re-

cess 60. The spring 58 is mounted under initial compression and constantly urges the wedge outwardly or to the right as viewed in Fig. 3. During closing movement of the door the wedge block 57 is engaged by the upper surface of the dovetail and is carried inwardly to some extent against the action of the spring, the wedge block will constantly tend to tighten itself against the upper surface of the abutment 53 and hence maintain the bolt 12 firmly in engagement with the tooth 54 on the striker thus minimizing the possible vibratory movement of the door in a vertical direction.

I claim:

1. In a latch mechanism for a swinging door, a support having a plate portion for disposition at the free edge wall of the door and having a flange extending from the inner edge thereof, a rotatable latch device pivotally mounted on said plate portion, detent means pivotally mounted on said plate portion and engageable with said latch device for holding the same in door latching position, outer manually operable means including a lever pivotally mounted on said plate portion for pivotally actuating said detent means thereby to disengage the latter from said latch device, a member mounted for swinging movement on said plate portion, and inner manually operable means comprising an actuator shiftable in opposite directions, two bell crank levers pivotally mounted on said flange for swinging movement about spaced axes, means pivotally connecting said actuator to said bell crank levers, one of said bell crank levers having a part thereof in opposing relation to a part of said detent means and the other of said bell crank levers having a part thereof in opposing relation to a part of said member, said actuator upon being shifted in one direction causing said one bell crank lever part to abut said detent means thereby to disengage the same from said latch device and said actuator upon being shifted in the opposite direction causing said other bell crank lever part to abut said member part and swing said member into a position in which a portion thereof will block pivotal movement of said first mentioned lever thereby to render said outer manually operable means ineffective to effect disengagement of the detent means from said latch device.

2. In a latch mechanism for a swinging door, a support having a plate portion for disposition at the free edge wall of the door and having a flange extending from the inner edge thereof, a rotatable latch device pivotally mounted on said plate portion, detent means pivotally mounted on said plate portion and engageable with said latch device for holding the same in door latching position, outer manually operable means including a lever pivotally mounted on said plate portion for pivotally actuating said detent means thereby to disengage the latter from said latch device, a member mounted for swinging movement on said plate portion, inner manually operable lever means, a shiftable link pivotally connected at one end to said lever means and longitudinally shiftable thereby in opposite directions, and two vertically spaced bell crank levers pivotally mounted on said flange each having a part thereof connected to the other end of said link, one of said bell crank levers having a part in opposing relation to a part of said detent means and the other of said bell crank levers having a part in opposing relation to a part of said member, whereby upon said link being shifted in one direction said one bell crank lever part will abut

the detent means part and pivotally actuate the detent means to disengage the same from said latch device and upon said link being shifted in the opposite direction said other bell crank lever part will abut said member part and swing said member into a position in which a portion thereof will block pivotal movement of said first mentioned lever thereby to render said outer manually operable means ineffective to effect disengagement of said detent means.

3. In a latch mechanism for a swinging door, a support having a plate portion for disposition at the free edge wall of the door and having a flange extending from the inner edge thereof, a rotatable latch device pivotally mounted on said plate portion, detent means pivotally mounted on said plate portion and engageable with said latch device for holding the same in door latching position, outer manually operable means including a lever pivotally mounted on said plate portion for pivotally actuating said detent means thereby to disengage the latter from said latch device, a member mounted for swinging movement on said plate portion, and inner manually operable means comprising an actuator shiftable in opposite directions, two bell crank levers pivotally mounted on said flange for swinging movement about spaced axes, means pivotally connecting said actuator to said bell crank levers, one of said bell crank levers having a part thereof in opposing relation to a part of said member and the other of said bell crank levers having a part thereof in opposing relation to one part of said detent means, said actuator upon being shifted in one direction causing said one bell crank lever part to abut said member part and swing said member into a position in which a portion thereof will block pivotal movement of said first mentioned lever thereby to render said outer manually operable means ineffective to effect disengagement of the detent means from said latch device, said member having a second part movable into the path of pivotal movement of a second part of said detent means when said member portion is disposed in blocking relation to said lever, said actuator upon being shifted in the opposite direction causing said other bell crank lever part to abut said one part of the detent means thereby to pivotally actuate the detent means to disengage the same from said latch device and to cause said second part of the detent means to abut said second part of said member and swing the same to position said portion thereof out of blocking position relative to the outer manually operable lever.

4. In a latch mechanism for a swinging door, a support having a plate portion for disposition at the free edge wall of the door and having a flange extending from the inner edge thereof, a rotatable latch device pivotally mounted on said plate portion, detent means pivotally mounted on said plate portion and engageable with said latch device for holding the same in door latching position, outer manually operable means including a lever pivotally mounted on said plate portion for pivotally actuating said detent means thereby to disengage the latter from said latch device, a member mounted for swinging movement on said plate portion, and inner manually operable means comprising an actuator shiftable in opposite directions, two bell crank levers pivotally mounted on said flange for swinging movement about spaced axes, means pivotally connecting said actuator to said bell crank levers, the point of connection of said

actuator to said bell crank levers being intermediate the pivot axes thereof, one of said bell crank levers having a part thereof in opposing relation to a part of said detent means and the other of said bell crank levers having a part thereof in opposing relation to a part of said member, said actuator upon being shifted in one direction causing said one bell crank lever part to abut said detent means thereby to disengage the same from said latch device and said actuator upon being shifted in the opposite direction causing said other bell crank lever part to abut said member part and swing said member into a position in which a portion thereof will block pivotal movement of said first mentioned lever thereby to render said outer manually operable means ineffective to effect disengagement of the detent means from said latch device.

5 5. In a latch mechanism for a swinging door, a support having a plate portion for disposition at the free edge wall of the door and having a flange extending from the inner edge thereof, a rotatable latch device pivotally mounted on said plate portion, detent means pivotally mounted on said plate portion and engageable with said latch device for holding the same in door latching position, outer manually operable means including a lever pivotally mounted on said plate portion for pivotally actuating said detent means thereby to disengage the latter from said latch device, a member mounted for swinging movement on said plate portion, and inner manually operable means comprising an actuator shiftable in opposite directions, two bell crank levers pivotally mounted on said flange for swinging movement about spaced axes, means pivotally connecting said actuator to said bell crank levers, said bell crank levers being constructed and arranged to swing simultaneously in opposite directions upon shifting of said actuator, said connecting means being fixed to one of said bell crank levers and being movable in a slot in the other of said bell crank levers, one of said bell crank levers having a part thereof in opposing relation to a part of said detent means and the other of said bell crank levers having a part thereof in opposing relation to a part of said member, said actuator upon being shifted in one direction causing said one bell crank lever part to abut said detent means thereby to disengage the same from said latch device and said actuator upon being shifted in the opposite direction causing said other bell crank lever part to abut said member part and swing said member into a position in which a portion thereof will block pivotal movement of said first mentioned lever thereby to render said outer manually operable means ineffective to effect disengagement of the detent means from said latch device.

6 6. In a latch mechanism for a swinging door, a support having a plate portion for disposition at the free edge wall of the door and having a flange extending from the inner edge thereof, a rotatable latch device pivotally mounted on said plate portion, detent means pivotally mounted on said plate portion and engageable with said latch device for holding the same in door latching position, outer manually operable means including a lever pivotally mounted on said plate portion for pivotally actuating said detent means thereby to disengage the latter from said latch device, a member mounted for swinging movement on said plate portion, inner manually operable lever means, a shiftable link pivotally connected at one end to said lever means

and longitudinally shiftable thereby in opposite directions, and two vertically spaced two arm bell crank levers pivotally mounted on said flange, each bell crank lever having one arm thereof pivotally connected to the other end of said link, one of said bell crank levers having a part of its other arm in opposing relation to a part of said detent means and the other of said bell crank levers having a part of its other arm in opposing relation to a part of said member, whereby upon said link being shifted in one direction said one bell crank lever arm part will abut the detent means part and pivotally actuate the detent means to disengage the same from said latch device and upon said link being shifted in the opposite direction said other bell crank lever arm part will abut said member part and swing said member into a position in which a portion thereof will block pivotal movement of said first mentioned lever thereby to render said outer manually operable means ineffective to effect disengagement of said detent means.

7 7. In a latch mechanism for a swinging door, a support having a plate portion for disposition at the free edge wall of the door and having a flange extending from the inner edge thereof, a rotatable latch device pivotally mounted on said plate portion, detent means pivotally mounted on said plate portion and engageable with said latch device for holding the same in door latching position, outer manually operable means including a lever pivotally mounted on said plate portion for pivotally actuating said detent means thereby to disengage the latter from said latch device, a member mounted for swinging movement on said plate portion, an inner manually operable actuator shiftable in opposite directions, and two vertically spaced two arm bell crank levers pivotally mounted on said flange, each bell crank lever having one arm thereof pivotally connected to said actuator, one of said bell crank levers having a part of its other arm in opposing relation to a part of said detent means and the other of said bell crank levers having a part of its other arm in opposing relation to a part of said member, said actuator upon being shifted in one direction causing said one bell crank lever arm part to abut said detent means thereby to disengage the same from said latch device and said actuator upon being shifted in the opposite direction causing said other bell crank lever arm part to abut said member part and swing said member into a position in which a portion thereof will block pivotal movement of said first mentioned lever thereby to render said outer manually operable means ineffective to effect disengagement of the detent means from said latch device.

8 8. In a latch mechanism for a swinging door, a support having a plate portion for disposition at the free edge wall of the door and having a flange extending from the inner edge thereof, a rotatable latch device pivotally mounted on said plate portion, detent means pivotally mounted on said plate portion and engageable with said latch device for holding the same in door latching position, outer manually operable means including a lever pivotally mounted on said plate portion for pivotally actuating said detent means thereby to disengage the latter from said latch device, a member mounted for swinging movement on said plate portion, an inner manually operable actuator shiftable in opposite directions, and two vertically spaced two arm bell crank levers pivotally mounted on said flange, means

pivots connecting one arm of each of said bell crank levers to said actuator, said connecting means being fixed to one of said arms and being movable in a slot in the other of said arms, one of said bell crank levers having a part of its other arm in opposing relation to a part of said detent means and the other of said bell crank levers having a part of its other arm in opposing relation to a part of said member, said actuator upon being shifted in one direction causing said one bell crank lever arm part to abut said detent means thereby to disengage the same from said latch device and said actuator upon being shifted in the opposite direction causing said other bell crank lever arm part to abut said member part and swing said member into a position in which a portion thereof will block pivotal movement of said first mentioned lever thereby to render said outer manually operable means ineffective to effect disengagement of the detent means from said latch device.

9. In a latch mechanism for a swinging door, a support having a plate portion for disposition at the free edge wall of the door and having a flange extending from the inner edge thereof, a rotatable latch device pivotally mounted on said plate portion, detent means pivotally mounted on said plate portion and engageable with said latch device for holding the same in door latching position, outer manually operable means including a lever pivotally mounted on said plate portion for pivotally actuating said detent means thereby to disengage the latter from said latch device, a member mounted for swinging movement on said plate portion, an inner manually operable actuator shiftable in opposite directions, and two vertically spaced two arm bell crank levers pivotally mounted on said flange, each bell crank lever having one arm thereof pivotally connected to said actuator, one of said bell crank levers having a part of its other arm in opposing relation to a part of said member and the other of said bell crank levers having a part of its other arm in opposing relation to one part of said detent means, said actuator upon being shifted in one direction causing said one bell crank lever arm part to abut said member part and swing the same into a position in which a portion thereof will block pivotal movement of said first mentioned lever thereby to render said outer manually operable means ineffective to effect disengagement of the detent means from said latch device, said member having a second part movable into the path of pivotal movement of a second part of said detent means when said member portion is disposed in blocking relation to said lever, said actuator upon being shifted in the opposite direction causing said other bell crank lever arm part to abut said one part of the detent means thereby to pivotally actuate the detent means to disengage the same from said

latch device and to cause said second part of the detent means to abut said second part of said member and swing the same to position said portion thereof out of blocking position relative to the outer manually operable lever.

10. In a latch mechanism for a swinging door, a support having a plate portion for disposition at the free edge wall of the door and having a flange extending from the inner edge thereof, a rotatable latch device pivotally mounted on said plate portion, detent means pivotally mounted on said plate portion and engageable with said latch device for holding the same in door latching position, outer manually operable means including a lever pivotally mounted on said plate portion for pivotally actuating said detent means thereby to disengage the latter from said latch device, a member mounted for swinging movement on said plate portion, an inner manually operable actuator shiftable in opposite directions, and two vertically spaced two arm bell crank levers pivotally mounted on said flange, means pivotally connecting one arm of each of said bell crank levers to said actuator, said connecting means being fixed to one of said arms and being movable in a slot in the other of said arms, one of said bell crank levers having a part of its other arm in opposing relation to a part of said member and the other of said bell crank levers having a part of its other arm in opposing relation to one part of said detent means, said actuator upon being shifted in one direction causing said one bell crank lever arm part to abut said member part and swing the same into a position in which a portion thereof will block pivotal movement of said first mentioned lever thereby to render said outer manually operable means ineffective to effect disengagement of the detent means from said latch device, said member having a second part movable into the path of pivotal movement of a second part of said detent means when said member portion is disposed in blocking relation to said lever, said actuator upon being shifted in the opposite direction causing said other bell crank lever arm part to abut said one part of the detent means thereby to pivotally actuate the detent means to disengage the same from said latch device and to cause said second part of the detent means to abut said second part of said member and swing the same to position said portion thereof out of blocking position relative to the outer manually operable lever.

JOHN H. ROETHEL.
